(57) **CLAIM**

The ornamental design for a desk fan, as shown and described.

DESCRIPTION

FIG. 1 is a front, right side and top perspective view of a desk fan showing my new design;

FIG. 2 is a rear, left side and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front and right side perspective view thereof, shown in an alternative state.

The dash-dash broken lines in the drawings depict the portions of the desk fan that form no part of the claimed design.
